**HIGH FREQUENCY COMPONENT EXHIBITING
MAGIC T PROPERTIES**Theodore S. Saad, Westwood, Mass., assignor to Sage
Laboratories, Inc., East Natick, Mass., a corporation
of MassachusettsFiled Nov. 6, 1964, Ser. No. 409,421
11 Claims. (Cl. 333—11)**ABSTRACT OF THE DISCLOSURE**

A cavity has opposed generally parallel conducting end walls for establishing an electric field generally perpendicular to the end walls. A conducting strip midway between and generally parallel to the end walls defines with respective ones of the end walls parallel plate transmission lines for coupling energy from a TEM input branch to intermediate branches in respective ones of the end walls that are coupled to the conducting strip. An odd mode branch is for establishing an odd TE mode in the cavity having electric field components perpendicular to the end walls so that when the branches are terminated in their respective characteristic impedances, energy applied to one of the TEM or odd mode branches divides substantially equally between the intermediate branches without reaching the other of the odd or TEM mode branches. With crystals terminating the respective intermediate branches a fifth terminal may be provided with a lead to the conducting strip for withdrawing energy at I-F frequency. In one embodiment of the invention the cavity is circularly cylindrical with circular end walls and a link coupling from the odd mode branch to the cavity. In another embodiment of the invention the cavity is essentially a portion of rectangular waveguide with the end walls comprising the broad walls of such a waveguide, and the odd mode branch comprises a rectangular opening for receiving energy from a rectangular waveguide of corresponding cross section.

The present invention relates in general to high frequency components exhibiting magic T properties and more particularly concerns a novel component especially useful in balanced mixing characterized by low noise and excellent port isolation. Not only does the invention exhibit excellent electrical properties, but it is relatively easy and inexpensive to fabricate and embodies a compact, rugged mechanical arrangement with an especially convenient arrangement of terminals.

A conventional waveguide magic T is a hybrid junction having four intersecting waveguide branches. Typically three of these branches are coplanar and form a T in defining the H plane junction. The fourth branch intersects the other three at right angles. It has hybrid properties of power division and isolation and the property of being substantially reflectionless for a wave propagating into the junction from any arm when the other three arms are matched terminated. While these properties have been achieved in coaxial devices, fabrication of such devices has been relatively costly and the arrangement of terminals not as convenient as desired.

Accordingly, it is an important object of this invention to provide a device having magic T properties that may be used to intercouple a plurality of coaxial transmission lines while keeping fabrication costs low and providing an exceptionally convenient arrangement of terminals.

Still another object of the invention is to achieve the preceding object while providing a high degree of port isolation.

Still another object of the invention is to provide a

2

balanced mixer in accordance with the preceding objects characterized by low noise properties.

According to the invention, conducting means define a cavity. Means define a TEM branch responsive to a potential applied at its input for establishing the TEM mode in the central region of the cavity and coating with first and second opposed wall portions of the cavity defining conducting means to define first and second two conductor transmission lines respectively between the TEM branch input and the cavity central region. First and second intermediate branches are arranged for coupling external devices to the central region and are respectively coupled to the TEM branch input by the first and second two conductor transmission lines, respectively. The first and second two conductor transmission lines are substantially the same electrical length. Means define an odd mode branch responsive to a potential applied at its input for establishing an odd TE mode in the central region of the cavity so that when the first and second intermediate branches are terminated in equal impedances, energy of a prescribed frequency applied to the odd mode branch is transmitted through the cavity to the intermediate branches in substantially equal amounts but of opposite electrical phase.

In a specific form of the invention the conducting means defines a hollow circular cylinder having first and second circular conducting end plates separated by a distance less than the cylinder diameter. The TEM branch input comprises a coaxial terminal pair in the curved conducting wall of the cavity defining conducting means with the terminal pair inner conductor being coupled to the central region by means including a conducting strip generally parallel to and midway between the circular conducting end plates. The first and second intermediate branches each comprise coaxial terminal pairs in respective ones of the first and second circular end plates with the inner conductor of each pair being coupled to the conducting strip in the central portion. The odd mode branch may comprise a coaxial terminal pair in the curved conducting wall with a link coupling the inner terminal of the latter pair to one of the end plates.

Numerous other features, objects and advantages of the invention will become apparent from the following specification when read in connection with the accompanying drawing in which:

FIG. 1 is a top view of an embodiment of the invention with the upper end plate removed;

FIG. 2 is an axial sectional view of an embodiment of the invention embracing section 2—2 of FIG. 1;

FIG. 3 is a top view with upper end plate removed of a variation of the embodiment of FIGS. 1 and 2 with the intermediate branch connections to the conducting strip staggered;

FIG. 4 is a view essentially thru section 4—4 of FIG. 3 but showing additional detail; and

FIG. 5 is a side view of an embodiment of the invention for mixing energy provided by a rectangular waveguide;

FIG. 6 is an end view of the embodiment of FIG. 5 as would be seen by an input rectangular waveguide; FIG. 7 is a view through section 7—7 of FIG. 5; and FIG. 8 is a view through section 8—8 of FIG. 6.

With reference now to the drawing, there is shown an especially advantageous embodiment of the invention in which the sides and bottom of the cavity defining means are formed by turning a solid conducting cylinder to form an annular wall with the desired inside diameter which typically corresponds to a half wavelength of a frequency within the operating range of the device. Thus, the bottom circular endplate 11 is contiguous with the curved wall 12 surrounding the cylindrical cavity axis

embraced by the upper intermediate branch inner terminal 13 and the lower intermediate branch inner terminal 14. An upper circular conducting endplate 15 completes the definition of the cavity.

The coaxial terminal pair 16 at the right, comprising an outer conductor 17 and an inner conductor 18 partially surrounded by an annular dielectric bead 21, functions as the input of the TEM branch. This TEM branch also comprises the conducting strip 22 midway between bottom endplate 11 and top endplate 15. Strip 22 coacts with these endplates to form upper and lower parallel plate transmission lines for coupling energy between the TEM input 16 and the central region of the cavity. The central region includes upper dielectric bead 23, coaxially surrounding the upper intermediate branch inner conductor 13, and lower dielectric bead 24, coaxially surrounding the lower intermediate branch inner conductor 14. The junction of these two conductors is connected to inner conductor 18 by strip 22. Inner conductors 13 and 14 are coaxially surrounded by upper outer conductor 25 and lower outer conductor 26, respectively, outside the cavity-defining casing to define upper and lower coaxial terminal pairs.

The left coaxial terminal pair 27 functions as the input to the odd mode branch and comprises an inner conductor 31 coaxially surrounded by an outer conductor 32. An L-shaped conductor 33 is connected from inner conductor 31 to a point 34 in bottom plate 11 to coact with the conductive casing and define a loop for effecting loop coupling between the coaxial terminal pair 27 and the inside of the cavity so as to establish an odd TE mode in the cavity. The tuning screws 35 in the upper end plate 15 above the elbow of conductor 33 coact therewith to adjust the effective capacity so as to improve the match presented at the coaxial terminal pair 27.

Turning now to the consideration of what are believed to be the principles of operation of the invention, it is convenient initially to assume that upper and lower intermediate branches are terminated in equal impedances. Then energy applied to the TEM input 16 establishes the field represented by vectors 36 and 37 when inner conductor 18 is positive with respect to the conductive casing. The energy transmission paths above and below conducting strip 22 are of substantially equal electrical length so that the energy divides and reaches inner conductors 13 and 14 in equal amounts and substantially in phase. The energy reaching that portion of the cavity embracing the link 33 would seem to establish an electric field consisting of vector components oriented like vectors 36 and 37, indicated as 36' and 37', of substantially equal magnitude but opposite phase so that virtually no potential is established between inner and outer conductors at branch 27.

Now consider the situation in which energy is applied to the odd mode branch 27. This is believed to establish an electric field represented by the vector 41 which may be broken down into an upper component 42 in the upper half of the cavity and a lower component 43 in the lower half of the cavity of substantially equal magnitude to that established in the upper half so that the upper and lower intermediate branches receive energy of substantially equal magnitude but of opposite phase for the inner conductor 13 will then be negative with respect to the conductive casing while the conductor 14 will be positive. Very little energy passes to the right to reach the TEM branch because the field at that point is oriented in the direction of vectors 42 and 43, as indicated by the vectors 42' and 43', so that the resultant field magnitude between the conducting plate 22 and the conductive casing is substantially zero. This mode of operation is believed to contribute largely to the properties of the device having high isolation over a relatively wide range of frequencies.

Referring to FIG. 3, there is shown a variation of the embodiment of the invention shown in FIGS. 1 and 2 with the connections from the intermediate branches to the conducting strip and a fifth terminal pair provided for

withdrawing intermediate frequency energy produced by mixing energy applied at the TEM branch and the odd mode branch. Where applicable, the same reference symbols identify corresponding elements throughout the drawing. The view of the structure seen in FIG. 3 is similar to the view seen in FIG. 1 with a few exceptions. In the structure of FIG. 3, especially advantageous for balanced mixing, the connections to conducting strip 22 at 51 and 52 are side-by-side along a diameter at right angles to the common axis of TEM input terminal pair 27. A dielectric support bead 53 is displaced from the connection points 51 and 52. A thin lead 54 connects the end of conducting strip 22 near connection point 52 to an output signal inner coaxial terminal 55 located in the outside wall 12 for delivering intermediate frequency energy to an external circuit. The outline of lower crystal 56 is visible in the view of FIG. 3.

Referring to FIG. 4, there is shown a sectional view essentially through section 4-4 of FIG. 3 to illustrate the crystals and supporting structure and the intermediate frequency output terminal in greater detail. The means for supporting lower crystal 56 and establishing the desired electrical connections is shown in detail in FIG. 4. The crystal holder includes a threaded sleeve 57 formed with an annular flange 61 abutting the bottom of the lower end wall 11 and force fit therein. A cup-shaped sleeve 62 formed with a shoulder 63 that rests against the top of conducting strip 22 has its narrow diameter end force fit in the opening of connection point 52 and has its upper end resting firmly against the piece of thin mylar insulating tape 64. A spring 65 of conducting material establishes firm electrical and mechanical contact with inner terminal 66 of lower crystal 56. The resulting structure establishes one contact between the crystal and conducting strip 22, helps to support the conducting strip 22 and maintains the integrity of the insulating relationship between the outside walls defining the cavity and the conducting strip 22.

Referring to FIGS. 5-8, there is illustrated an embodiment of the invention arranged for mixing a signal applied at the TEM coaxial terminal pair 71 with a signal provided at the odd mode branch 72, arranged to mate with a rectangular waveguide, to provide an intermediate frequency signal on output terminal 70 in response to the mixing action effected by crystals 73 and 74 terminating intermediate branches 75 and 76, respectively. The crystal holders comprise an assembly of well known design including crystal current monitoring caps.

The portion 77 of conducting strip 78 near the center of the cavity is connected to first and second diode contact receptacles 81 and 82, respectively, for receiving contacts 83 and 84 of diodes 73 and 74, respectively. First and second insulating sleeves 85 and 86, which may be of rexolite material, surround diode contacts 81 and 82, respectively and diodes 73 and 74, respectively and help support conducting strip 78.

The intermediate frequency coaxial signal terminal 70 is supported within an insulating sleeve 107 which in turn carries an annular conducting sleeve 108. A thin conducting wire 111 connects the nearest corner of conducting strip 78 to the inside end of the IF terminal 70. The latter end is bypassed to ground by inductor 112. A tuning post 113 is located near the corner 114 of conducting strip 78 to adjust the effective reactance so as to improve the match presented at the waveguide terminal 72.

The particular structure of FIGS. 5-8 forms an especially convenient means for mixing an input signal provided by a waveguide with a local oscillator signal provided over a coaxial cable in a compact physical configuration providing a convenient means for deriving the output signal while maintaining exceptionally high electrical performance.

An embodiment of the type disclosed in FIGS. 5-8 operates over the frequency range of 3,600 to 4,200 megacycles using type 1N416 crystals to provide an intermediate frequency of 70 megacycles with a noise figure of

8 db while maintaining an isolation of greater than 25 db between local oscillator and signal ports.

In an exemplary embodiment of the invention actually constructed of the type shown in FIGS. 1 and 2 for operation over a frequency range of 5.4 gigacycles to 6.0 gigacycles, the four coaxial terminal pairs were conventional type N connectors, the inside diameter of the cavity was 1.6", the inside height of the cavity was $\frac{1}{2}$ ", the diameter of the annular Teflon dielectric beads 23 and 24 was 0.4", the width of strip 22 was .550", its length to the constricted portion was .750", and point 34 was located .440" from the inside wall.

With the upper and lower intermediate branches terminated in coaxial crystal holders with type 1N23E crystals and TEM input 16 energized with local oscillator signal of 2 mw. and at 6,000 mc. and odd mode input 27 energized with the signal input at 6,030 mc., an intermediate frequency signal at 30 mc. was provided with a noise figure of 6.7 db while maintaining an isolation between signal and local oscillator ports of 22.5 db.

The first exemplary embodiment of the invention described herein embodies a circular cylindrical cavity and includes loop coupling to establish the odd mode. Other cavity shapes, such as rectangular, elliptical and spherical may be employed within the principles of the invention. Other means, such as probe coupling may also be employed to establish the odd mode. The specific embodiments and uses described herein are by way of example only. It is apparent that those skilled in the art may now make numerous modifications and uses of and departures from the specific embodiments described herein without departing from the inventive concepts. Consequently, the invention is to be construed as limited only by the spirit and scope of the appended claims.

What is claimed is:

1. A high frequency component exhibiting magic T properties comprising,

conducting means defining a cavity having first and second parallel opposed end wall portions, means defining a TEM branch responsive to a potential applied at its input for establishing the TEM mode with electric field perpendicular to said end walls in the central region of said cavity and including a conducting strip midway between, parallel to and coacting with said first and second opposed end wall portions of said conducting means to define first and second two conductor transmission lines respectively between said TEM branch input and said central region, said end wall portions separated by substantially the same distance throughout said cavity, first and second intermediate branches in respective ones of said end wall portions for coupling external devices to said central region and respectively coupled to said TEM branch input by said first and second two conductor transmission lines respectively, first and second leads perpendicular to said first and second end wall portions coupling said first and second intermediate branches respectively to a point on said conducting strip substantially at the center of said cavity, said first and second two conductor transmission lines being of substantially the same electrical length, and means defining an odd mode branch responsive to a potential applied at its input for establishing an odd TE mode in said central region so that when said first and second intermediate branches are terminated in equal impedances, energy of a prescribed frequency applied to said odd mode branch is transmitted through said cavity to said intermediate branches in substantially equal amounts but of opposite electrical phase.

2. A high frequency component exhibiting magic T properties in accordance with claim 1 wherein,

said conducting means defines a hollow circular cylinder having first and second circular conducting end

plates separated by a distance less than the cylinder diameter,

said TEM branch input comprises a coaxial terminal pair in the curved conducting wall of said conducting means with the terminal pair inner conductor being coupled to said central region by means including said conducting strip generally parallel to and midway between said circular conducting end plates, said first and second intermediate branches each comprise coaxial terminal pairs, said first and second intermediate branch pairs being in said first and second circular end plates with the inner conductor of each pair being coupled to said conducting strip in said central portion.

3. A high frequency component exhibiting magic T properties in accordance with claim 2 wherein,

said odd mode branch comprises a coaxial terminal pair in the curved conducting wall opposite to said TEM branch input coaxial terminal pair and a link coupling the inner terminal of the latter pair to one of said end plates.

4. A high frequency component exhibiting magic T properties in accordance with claim 1 and further comprising,

first and second unilaterally conducting devices terminating said first and second intermediate branches respectively, and an output terminal coupled by a lead extending through and insulatedly separated from said cavity defining conducting means to said central region for extracting energy from said central region.

5. A high frequency component exhibiting magic T properties in accordance with claim 2 and further comprising,

first and second unilaterally conducting devices terminating said first and second intermediate branches respectively, and an output terminal extending through and insulatedly separated from said cavity defining conducting means coupled to said conducting strip near the end thereof in said central region.

6. A high frequency component exhibiting magic T properties in accordance with claim 5 wherein,

said odd mode branch comprises a coaxial terminal pair in the curved conducting wall opposite to said TEM branch input coaxial terminal pair and a link coupling the inner terminal of the latter pair to one of said end plates.

7. A high frequency component exhibiting magic T properties in accordance with claim 1 wherein,

said odd mode branch comprises means defining a rectangular opening for engaging a rectangular waveguide.

8. A high frequency component exhibiting magic T properties in accordance with claim 7 and further comprising,

first and second unilaterally conducting devices terminating said first and second intermediate branches respectively,

and an output terminal coupled by a lead extending through and insulatedly separated from said cavity defining conducting means to said central region for extracting energy from said central region.

9. A high frequency component exhibiting magic T properties in accordance with claim 8 wherein,

said conducting means defines a hollow rectangular waveguide cavity having broad and narrow walls, said TEM branch input comprises a coaxial terminal pair in one of said narrow walls with the terminal pair inner conductor being coupled to said central region by means including a conducting plate generally parallel to and midway between said broad walls,

said first and second intermediate branches each comprise coaxial terminal pairs,

said first and second intermediate branch pairs being in respective ones of said broad walls with the inner conductor of each pair being coupled to said conducting strip in said central portion.

10. A high frequency component in accordance with claim 9 wherein said cavity defining means includes an end wall generally perpendicular to said broad and narrow walls and said output terminal extends through and is insulatedly separated from the latter end wall and coupled to said conducting plate near a corner thereof in said central region near said latter end wall.

11. A high frequency component exhibiting magic T properties in accordance with claim 7 wherein, 15
said conducting means defines a hollow rectangular waveguide cavity having opposed broad walls perpendicular to opposed narrow walls, 20
said TEM branch input comprises a coaxial terminal pair in one of said narrow walls with the terminal pair inner conductor being coupled to said central region by means including said conducting plate generally parallel to and midway between said broad walls,

said first and second intermediate branches each comprise coaxial terminal pairs, 5
said first and second intermediate branch pairs being in respective ones of said broad walls with the inner conductor of each pair being coupled to said conducting strip in said central portion.
